UNITED STATES PATENT OFFICE

HENRY SHAPIRO, OF PHILADELPHIA, PENNSYLVANIA

GARMENT HANGER

Application filed October 10, 1927. Serial No. 225,088.

This invention relates to garment hangers, and particularly to garment hangers having means thereon for preventing the dislodgement of the garment.

The garment hanger herein shown and described is particularly adapted for use in hanging the wearing apparel of women, which are oftentimes of a silky and flimsy nature so that they are readily dislodged from the ordinary hanger which has no means for securing them thereon.

The object of this invention is to produce a garment hanger which will retain the garment in position thereon.

Another object is to provide a garment hanger having operable means for clamping the garment thereon.

Another object is to provide simple and efficient means for securing a garment on a hanger.

Another object is to provide a garment hanger such as above described which will have few and simple parts, and which may be readily and economically manufactured.

The invention consists of a garment support having arranged in connection therewith a plurality of clamping members and a member turnable to various positions for rendering the clamping members effective or ineffective for clamping purposes as the case may be, the connection of such said member with the clamping members being such as to operate the clamping members simultaneously for both directional movements of said member.

The drawings illustrate an embodiment of the invention and the views therein are as follows:—

Figure 1 is a front view of a garment hanger showing the parts in clamped or closed position,

Figure 2 is a top plan view of same,

Figure 3 is a view similar to Figure 1 and shows the clamping parts in open position,

Figure 4 is a vertical sectional view on the line 4—4 of Figure 1, and looking in the direction of the arrows;

Figure 5 is a vertical sectional view on the line 5—5 of Figure 3, and looking in the direction of the arrows,

Figure 6 shows a hanger having a modified clamping mechanism,

Figure 7 is a vertical sectional view on the line 7—7 of Figure 6, and looking in the direction of the arrows, and

Figure 8 is a like view on the line 8—8 of Figure 6, and looking in the direction of the arrows.

Referring to the drawings, and particularly to the device shown in Figures 1 to 5 inclusive, the hanger comprises a supporting member 11, a hook 12 for hanging the same, a bracket 13, a gripping member 14 and a locking mechanism 15.

The garment supporting member 11 is of the usual curved type and the bracket 13 is adapted to straddle the same at its center and be connected thereto by some fastening means, such as pins or rivets 16. The bracket has upstanding guides 17 and 18 on opposite sides of the straight portion 19 of the hook 12. These guides are struck up from the middle of the bracket which is composed of sheet metal bent to form, and on the outer sides of these upstanding guides the metal forming the upper part of the bracket is sawed out and bent under to provide inturned lips 21 which together with the top of the bracket form means for holding the gripping member 14.

The gripping member 14, formed of thin spring metal, is bowed and is in the shape of an arc whose radius is smaller than the radius of the supporting member 11 so that it has a natural tendency to bear down upon the top of the supporting member at its ends when its center is held close to the supporting member. These ends are provided with pads 22 which are suitably secured to said gripping member by eyelets 23 or other means and said pads are composed of soft material such as felt which press upon the garment and will not injure the same.

The locking mechanism, which is formed of heavy wire, when considered in its closed position comprises a pair of vertical legs 25 extending down the side of the supporting member and which terminate at their lower ends in an inturned loop 24, while the upper ends of said legs are curved over the top of said supporting member and outwardly. The

outwardly extending portions have short straight portions 26 which extend through the guides 17 and 18 and downwardly extending arms 27, the ends of which are slidably mounted in clamps 28 mounted on the gripping member 14.

The bottom end of the straight portion 19 of the hook 12, which extends through the supporting member 11, is provided with a 10 rivet head 29 thereon for preventing its removal and this rivet head forms a button over which the looped end of the inturned loop 24 is snapped when the locking mechanism is closed.

15 The guides 17 and 18 have horizontal slots 31 in each of the same and the forward end thereof, i. e. the side on which the vertical legs of the locking device operate is provided with a recess 32 which permits the straight portions 26 to be drawn downward therein as the looped portion 24 passes over the rivet head or button 29.

Figure 3 shows the locking device in its open position; the looped end 24 having been 25 released from the rivet head or button 29 and pushed upward so that the said loop straddles the straight portion 19 of the hook 12. The arms 27 which have been rotated 180° to open the gripping member 14 have raised 30 the ends thereof by means of the clamps 28 so that the pads on the ends of said gripping member have been raised a considerable distance above the supporting member 11 which allows for the removal from, or insertion of, a garment on the supporting member 11.

When the locking device is operated, the lower face of the slots 31 in the upstanding guides 18 act as fulcrums for the arms 27 for 40 raising and lowering the pads 22.

The upstanding guide 17 is provided with a slot 33 which permits the locking device to be attached to the garment hanger after the gripping member 14 is in place.

45 Figures 6, 7 and 8 illustrate a garment hanger in which the garment is held in place by the eyelets 34 on the downwardly extending ends 35 of the locking member. The locking member in this modification with 50 this exception is exactly the same as the locking device already described. The supporting member 36 is formed from thin sheet metal pressed to substantially channel-shape and the bracket 37 including the upstanding guides 38 and 39 which are exactly the same as the bracket 13 already described are stamped out of the metal forming the supporting member. At the center of the bottom of the supporting member is a bent and 55 curved portion 41 which takes the place of the rivet head on the bottom of the straight portion of the hook and over which the curved 24 of the locking device is adapted to snap to lock the eyelets 34 in close engagement with the supporting member.

In place of the gripping member 14, this modification is provided with a short spring member 42 which has a tendency to draw the upwardly extending arms 43 of the locking device upward when in closed position so as to hold the inturned loop 24 in locked position on the part 41.

70 By placing slots 44 in the guideways in the upstanding guides 38 and 39, the straight portions 26 of the locking member may be dropped into the slots 31 and the clamps 28 may be passed over the ends of the eyelets 34 and brought around to position on the outwardly extending arms 43 of the locking device and secured to the spring 42.

75 In both instances the straight portion 26 and the downwardly extending portions 27 and 43 of the locking device are off-center so as to maintain the inturned loop in either an open or closed position.

80 Various changes and adaptations may be made in the embodiments of the invention as above described within the scope of the invention as hereinbefore set forth and hereinafter claimed.

85 I claim:

1. A garment hanger comprising a supporting member, a bracket in the center of the same, a gripping member supported by said bracket and having free ends adapted to grip and hold a garment on said supporting member, and means on said bracket for raising the free ends of said gripping member and for lowering said free ends to grip a garment on said supporting member.

90 2. A garment hanger comprising a supporting member, a bracket in the center of the same, a gripping member supported by said bracket and having free ends adapted to grip and hold a garment on said supporting member, means on said bracket for raising the free ends of said gripping member and for lowering said free ends to grip a garment on said supporting member, and means for locking said last named means in closed position.

95 3. A garment hanger comprising a supporting member, a bracket centrally located thereon, a gripping member supported by said bracket and having free ends normally adapted to secure a garment on said supporting member, and means mounted on said bracket and engaging said gripping member for raising the ends thereof and for locking the ends to secure a garment on said supporting member.

100 4. A garment hanger comprising a supporting member, a gripping member supported at the center of said supporting member and having free ends, and means pivoted to the supporting member for simultaneously operating both ends of said gripping member for gripping a garment between said supporting member and both ends of said gripping member.

105 5. A garment hanger comprising a sup-

porting member, a bracket secured to the center thereof and having upstanding guides, a spring gripping member having free ends and centrally supported on said bracket, a locking member having arms extending out from each side of said bracket and secured to said gripping member, and an operating portion on said locking mechanism for raising the free ends of said gripping member 10 and for lowering the same and exerting pressure on a garment supported on said supporting member.

6. A garment hanger comprising a supporting member, a single resilient gripping 15 member centrally supported and having free ends, and means for simultaneously moving and locking the free ends into or out of engagement with said supporting member.

7. A garment hanger comprising a rigid 20 supporting member, a resilient gripping member associated at its middle with the middle of the rigid member and a latch pivoted at the joint middle of the members and having arms extending upon opposite sides of 25 the middle and connected with the resilient member intermediate the middle and ends.

8. A garment hanger comprising a rigid supporting member, a resilient gripping member associated at its middle with the 30 middle of the rigid member and a laterally swinging latch at the joint middle of the members and having arms extending upon opposite sides of the middle and connected with the resilient member intermediate the middle 35 and ends.

9. A garment hanger comprising a rigid supporting member, a resilient gripping member associated at its middle with the middle of the rigid member and a laterally swinging 40 latch at the joint middle of the members and having arms extending upon opposite sides of the middle and bearing upon the resilient member intermediate the middle and ends.

45 10. A garment hanger comprising a rigid supporting member, a resilient gripping member associated at its middle with the middle of the rigid member and a laterally swinging latch at the joint middle of the members 50 and having bent arms extending upon opposite sides of the middle and bearing upon the resilient member intermediate the middle and ends.

In testimony whereof I have signed my 55 name to this specification.

HENRY SHAPIRO.
